UNITED STATES PATENT OFFICE.

STANLEY HICKS, OF NORTH YAKIMA, WASHINGTON.

CURRENT-MOTOR.

1,071,918.

Specification of Letters Patent.

Patented Sept. 2, 1913.

Application filed June 29, 1912. Serial No. 706,573.

To all whom it may concern:

Be it known that I, STANLEY HICKS, residing at North Yakima, in the county of Yakima and State of Washington, have invented certain new and useful Improvements in Current-Motors, of which the following is a specification.

This invention relates to that class of current motors in which the current wheel is adapted to be submerged in any river, or brook, artificial water-falls, or any other water body, in which there is a swift current.

My invention seeks to provide a current motor, or water wheel of the character described more especially designed for use at places where the propulsive powers of a moving body of water could not otherwise be economically utilized and my said invention further has for its purpose to provide a current motor of a very simple and economical construction, which may be readily put up without the aid of skilled labor or special machinery, and in which the parts are coöperatively so arranged that they are not easily injured by debris passing down the stream and which will effectively serve for its intended purposes.

Another object of my invention is to provide a current drive wheel having an improved construction of wings or blade members whereby to concentrate the force of the water against them for acquiring a maximum impelling power of the current, and at the same time causing the current of the water to continuously flow to the outer edge of the said wings or blades, and in such a manner that the current is held within its natural course, as well as overcoming the tendency of a flow of water racing to the center or axial point of the wheel, thereby preventing eddies or back pressure against the wings or blades.

With still further objects in view that will be hereinafter apparent, my invention consists in the peculiar combination and arrangement of the parts hereinafter fully described, specifically pointed out in the claims, and illustrated in the accompanying drawings, in which:

Figure 1, is a perspective view of my invention, and the same illustrates, in a general way, an operative application thereof. Fig. 2, is a plan view of a plurality of my improved current wheels attached to a power transmitting shaft. Fig. 3, is an end view of one set of blades or vanes, the shaft

therefor being shown in section. Fig. 4, is a detail perspective view of one of the blade supports carried on the shaft. 60

In the practical application of my improved current motor or wheel, as many of the said wheels are mounted on a common shaft 1 as the condition of the current into which the wheels are to be mounted, and the character of the mechanism to be operated, 65 may make it desirable.

In Fig. 1 of the drawings, I have shown my construction of current wheel mounted in a creek or sluice-way and the shaft is 70 journaled in bearings 2 secured upon the lower ends of hangers 3, pendent from the cross timbers 4 which are supported on the banks of the creek and which are braced to the vertical extensions of the members 3 75 which latter, in turn are joined by a longitudinal or head timber 5.

My invention is embodied in the wheel structure and the same comprises a central support 10, which in the simplest and cheapest form of my invention is a piece of timber centrally apertured as at 11 for the passage of the shaft, it being made fast to the said shaft to turn therewith in any approved manner. The opposite ends of each 85 supporting member 10 are beveled at an acute angle to the shaft 1, and upon each of the said beveled ends is bolted a laterally projecting arm 12. Upon each of the cross arms 12 is mounted a wing or blade 13 pref- 90 erably formed of sheet metal bent to the desired shape and securely bolted to the side of the supporting bar that faces the current, as is clearly shown in Figs. 1 and 2 of the drawings, by reference to which it 95 will also be noted that the beveled edges of the arm 12 are relatively such that the pairs of arms 12 with their blades are inclined in planes at approximately right angles to each other, the reason for which will presently 100 appear. Each blade 13 comprises a body that includes a flat impacting face 16 and a flange 17 that is bent forwardly from the face of the said blade and at approximately right angles thereto as clearly shown in the 105 drawings. The flange 17 of each blade includes a forward or water penetrating portion that is disposed at an acute angle with respect to the shaft 1 and a rear portion that is substantially parallel with the inner edge 110 of the blade face 16, as is clearly shown in Fig. 2 of the drawing. The flanged edges of the blades are formed of two integrally connected portions disposed at an obtuse

angle to each other. As before stated, the blades or wings are mounted at acute angles to the shaft, and the two opposite blades of each set relatively at right angles to each other, and by reason thereof it follows that when the blades are set in the current with their flat faces 16 facing the incoming stream, the current in engaging the blades is continuously deflected toward the outer edges of the blades and in its natural course, the inclination of the flanges causing the current, as it passes over the blades, to effect a secondary thrust action on the blades, by reason of striking the flanges as it passes outwardly thereagainst. Again by reason of the relative inclinations of the blades, it is apparent that since the uppermost blade inclines in the direction of movement of the incoming current, and the lowermost blade inclines toward the said incoming current, the latter thereby receives the maximum force or impact of the current and it, in consequence, creates a continued rotation of the shaft 1 in one direction. Another and important advantage obtained in the construction and arrangement of my blades is that the said blades in turning cut the water at substantially right angles to the current and hence the frictional resistance of the wheels in rotation through the water, is reduced to the minimum.

By reason of the peculiar set of the wheels to the current, the water receiving face of the wheel blades have each two inclinations with respect to the direction of the current, and since these are at right angles to each other, one of the faces receives the direct impulse or impact force of the current wheel, the other face or inclinations causing a slanting pressure of the impacting water that creates a commutative force that produces a powerful and continuous rotation of the wheel from a slowly moving current.

When using a plurality of my improved wheels on a common shaft, the said wheels are set so their blades are positioned at right angles to each other, the advantage of thus setting the wheels being apparent from Fig. 3 of the drawings which shows when thus set, four wings or paddles stand in the line of the current for simultaneously acting upon. Another advantage developed in my type of current wheel is, that the creating of eddies or back pressure on the blades is eliminated and the danger of the fluid wedging between the blades is also overcome.

The power transmitted to the shaft may be taken from a pulley 45 thereon and belted to a pulley on a driven shaft mounted on top of the framing.

What I claim is:

1. A water wheel having its shaft pro-

jected in the direction of the current and provided with paddles or blades arranged in oppositely disposed pairs, transversely mounted with respect to the said shaft, each pair of the said paddles or blades including a supporting member perpendicular to the said shaft and attached to the shaft, the outer ends of the said member being beveled to an obtuse angle with the flow of the current, an arm attached to each end of the said member, the said arms being extended laterally outward from their respective ends of the member to which they are attached and flat blades secured to the obtusely beveled faces of their respective arms.

2. A water wheel having its shaft projected in the direction of the current and provided with paddles or blades arranged in oppositely disposed pairs, transversely mounted with respect to the said shaft, each pair of the said paddles or blades including a supporting member perpendicular to the said shaft and attached to the shaft, the outer ends of the said member being beveled to an obtuse angle with the flow of current, an arm attached to each end of the said member, the said arms being extended laterally outward from their respective ends of the member to which they are attached and flat blades secured to the obtusely beveled faces of their respective arms, the said blades including flanges at their outer edges that project forwardly approximately at right angles to the body of the blades.

3. A water wheel having its shaft projected in the direction of the current and provided with paddles or blades arranged in oppositely disposed pairs, transversely mounted with respect to the said shaft, each pair of the said paddles or blades including a supporting member perpendicular to the said shaft and attached to the shaft, the outer ends of the said member being beveled to an obtuse angle with the flow of current, an arm attached to each end of the said member, the said arms being extended laterally outward from their respective ends of the member to which they are attached and flat blades secured to the obtusely beveled faces of their respective arms, the said blades including flanges at their outer edges that project forwardly approximately at right angles to the body of the blades, the flanges of each blade including a front water penetrating portion disposed at an acute angle to the shaft and a remaining portion disposed substantially parallel to the shaft and the inner edge of the face of the blade.
